UNITED STATES PATENT OFFICE.

HARRY D. BROWN, OF LOS ANGELES, CALIFORNIA, ASSIGNOR TO CINEMA STUDIOS SUPPLY CORPORATION, OF LOS ANGELES, CALIFORNIA, A CORPORATION OF CALIFORNIA.

RHEOSTAT.

Application filed April 8, 1926. Serial No. 100,502.

This invention relates generally to rheostats, as is more particularly concerned with structural features of a type of rheostat especially well adapted for use in connection with arc-lamps such as are employed for illuminating motion picture sets and the like, though the invention, considered in its broader aspects is not limited to such adaptation.

10 Lamps used in situations mentioned above, are subject to very considerable abuse, and it is, therefore, one of the objects of the invention to provide a rheostat which will stand up well under the severe service conditions to which it is exposed. It is also among the objects to provide a structure which is comparatively simple, capable of being easily and quickly assembled and disassembled, compact, and highly efficient in operation.

15 However, it may be considered as the principal object of the invention to provide a rheostat made up of a plurality of resistance elements, whereby should a break occur in the resistance wire, only that element 20 in which the break occurs, need be replaced. This feature is in contra-distinction to the usual rheostat wherein the resistance wire is one continuous coil, so in the event of a break, the entire coil must be replaced, a task which consumes considerable 25 time and involves considerable expense, as will be readily appreciated by those skilled in the art.

Each resistance element of my device is 30 self-contained, the several elements being detachably connected to common bus rings which are longitudinally spaced along the vertical post of the supporting frame. The structural features of bus-ring support, the 35 make-up of the elements, and other objects and novel features of the invention will be made apparent in the following detailed description, reference being had to the accompanying drawings, in which:

40 Fig. 1 is a side elevation of a lamp equipped with a rheostat embodying my invention;

Fig. 2 is an enlarged elevation of the lamp standard or supporting frame, the rheostat casing being removed to expose the resistance 45 elements;

Fig. 2^a is a plan section on line 2^a—2^a of Fig. 2;

Fig. 3 is a section on line 3—3 of Fig. 2;

Fig. 4 is an enlarged section on line 4—4 of 50 Fig. 2, the view of the assembly being shown

as rotated somewhat from the position of Fig. 2 to bring the resistance elements square with the sheet;

Fig. 5 is a section on line 5—5 of Fig. 4;

Fig. 6 is a section on line 6—6 of Fig. 4; 60

Fig. 7 is a fragmentary perspective view of a resistance element;

Fig. 8 is a plan view of the terminal cap shown in Fig. 7, as viewed from beneath; 65 and

Fig. 9 is an enlarged, contracted section on line 9—9 of Fig. 2^a.

In the drawings, I have shown a standard or supporting frame F which includes a horizontally arranged base spider S made up of a casting 10 and base rods 11. Casting 10 includes a central hub 12 having an upwardly opening socket 13 into which vertical, tubular post 14 is screwed, and from which extend a plurality (preferably, three) radial, hollow 70 base arms 15. Hollow rods 11 are slipped into arms 15 and secured in position by rivets 16. Casting 10 preferably has bracing ribs 75 17 extending between arms 15.

Clamped at 18 to the ends of rods 11 are 80 angle castings 19 to which are secured caster assemblies 20. Castings 19 also have upwardly and inwardly inclining extensions 21 to which the lower extremities of braces 22 are secured at 23. Braces 22 incline towards 85 and are secured to arms 24 of frame casting 25, said casting having a central hub 26 which is drilled out to take post 14. Integral with casting 25 is a split spring collar 27 which is adapted to be sprung by clamp nut 28 into 90 clamping engagement with vertical lamp-rod 29, the latter being of such diameter that it has sliding fit within the bore of post 14. Rod 29 carries a table 30 at its upper end, this table supporting uprights 31 from which lamp casing 32 is pivotally hung. By loosening nut 28, it will be seen that rod 29 may be shifted vertically through post 14 to vary the 95 height of the lamp, or that said rod may be rotated to swing the lamp about.

I will now describe the preferred structure and manner of supporting the improved rheostat, as generally indicated by the letter R, but it will be understood the invention, considered in its broader aspects, is not limited 100 to the particularities of construction here set forth in detail, the detailed description being given merely that a clear understanding may be had of an illustrative embodiment of the 105 invention.

I provide a circular bottom plate 33 (co-axial with and centrally apertured at 34 to take post 14) which is adapted to rest on the radially spaced lugs 35 and 36 provided on the upper side of each casting arm 15, the inner lugs 36 having threaded bores 37 adapted to take bolts 38.

Plate 33 has an annular, upwardly, extending flange 39 near its outer edge, and has upper and lower bosses 40 which are in alignment with bosses 36. A bottom bus ring B, of material such as cast brass or other metals having suitable current-conductive characteristics, has downwardly extending bosses 41 which are arranged to be in vertical alignment with bosses 36 and 40, but insulating washers 42 are interposed between bosses 41 and plate 33. Anchor bolts 38 pass, preferably with considerable clearance, through bus-ring bosses 41, and thence through washers 42 and plate 33 into bosses 36, the heads of the bolts being insulated from the bus rings by washers 43. Bolts 38 hold casting 10, plate 33 and bus ring B in assembly, but it will be seen that the bus ring is entirely insulated from plate 33, casting 10 and post 14; the central opening 44 of the bus ring being of considerably greater diameter than that of post 14 so that there may be an ample air gap between ring and post.

Extending upwardly from and integral with ring B are attachment lugs 45 whereby the bus ring is electrically connected to the individual resistance elements E which may be provided singly or in any desired number, within reasonable limits. Since the elements are identical, I will describe but one in detail. The supporting body or wire rack W of the element is made up of a main, elongated plate 46 and a pair of relatively narrow transverse plates 47, the latter extending at substantially right angles with respect to and from opposite sides of said main plate, said transverse plates preferably being located approximately midway between the edges 48 of the main plate. Therefore, considered in transverse cross-section the plates have the configuration of a cross with a pair of oppositely disposed long arms and a pair of oppositely disposed and centrally disposed short arms. The plates are made of any material having suitable non-current-conductive characteristics (I find "transite" to be particularly well suited to the purpose) and their exposed edges are preferably serrated as at 49 to provide grooves whereby the coils of resistance wire 50, wound spirally about the rack, may be kept separated. The wire 50, having characteristics usual to resistance wires of rheostats, is wound with sufficient tension to retain it in contact with the exposed edges, only, of the plates, the major extent of the wire thus being held from the plates, with obvious advantage.

The opposite ends of the wire spiral are

connected as at 51 (Fig. 2) to upper and lower terminal caps 52 and 53, respectively, which are of cast brass or other metal having suitable current-conductive characteristics. Each cap consists of a body portion 54 of cross-shape, the upper and lower cap of a given pair having oppositely opening sockets 56 having the same horizontal cross-section characteristics of the rack, that is, the sockets have relative long portions 57 adapted to take the opposite ends of plate 46 and have relatively short transverse portions 58 adapted to take the opposite ends of plates 47. While the ends of all the plates may have friction tight fit within the caps, I preferably provide bolts 59 through the caps and main plates so the caps may be held positively from displacement with respect to the rack.

Extending from the top and bottom, respectively, of the upper and lower terminal caps, are attachment lugs 60 which are preferably slotted at 61 to take bolts 62, the latter being adapted releasably to draw lugs 60 into tight facial engagement, and therefore electrical connection with the associated lugs 45 or 45' of bus rings B and B', respectively, said ring B' being similar to ring B but being reversed, top for bottom, so its lugs 45' extend downwardly. The terminal caps are thus releasably secured in electrical connection with their associated bus rings and current may pass from a given bus ring, through wire 50 and thence to the other bus ring. It will also be apparent that bolts 62 form the connection whereby the wire racks are supported by the bus rings.

Bus ring B' is suspended by bolts 38^a from a top plate 63 which is generally similar to bottom plate 33 except that its annular flange 64 extends downwardly, and it has a central hub 65 to take post 14; a set screw 66 or equivalent means preferably being provided through the hub and adapted to engage post 14 frictionally so the top plate and top bus ring are held releasably in spaced relation along the post with respect to the bottom plate and bus ring.

Bolts 38^a are insulated from ring B' by air gap 67 and washer 68, while said ring is insulated from plate 63 by a ring 69 of insulating material such as "transite".

It will be seen that the resistance elements and bus rings are entirely insulated from the supporting standard or frame F.

Extending about the rheostat is a metal casing C which preferably is perforated at 70 to provide ventilation, the casing being in the form of a band drawn around flanges 39 and 64, with its free ends overlapped and detachably secured together as by screws 71 (Fig. 1).

Should the wire of a given element break or burn out, it will be seen that it is a matter of ease to strip the casing from the rheostat, detach the defective element from the bus rings, and replace it; all without in any way dis-

turbing such elements as are in good order. Not only is a saving in time thus effected, but wire is also saved, since only a portion of the total wire length of the rheostats need be replaced.

5 Wires W' lead from lamp switch 72 through insulating bushings 73 in plate 63 and extend one to each of bus rings B and B'. The wires may be clamped in electrical 10 connection to the rings by any suitable means, preferably easily releasable; for instance, by clips 74 which are screwed to rings.

15 It is believed a full understanding of the invention will be had from the foregoing, but the drawings and description are to be considered merely as illustrative of and not restrictive on the broader claims appended hereto, for various changes in design, structure and arrangement may be made without 20 departing from the spirit and scope of said claims.

I claim:

1. In combination with the supporting 25 frame of a lamp which frame includes a base member having a substantially centrally arranged, vertical post; a rheostat embodying a pair of bus rings spaced apart longitudinally along and insulated from the post, and a plurality of angularly spaced resistance 30 elements arranged about the post, each element embodying a wire-rack having non-conduc-

tive characteristics, spaced terminals on said rack, and resistance wire wound about said rack between and terminally connected to said terminals; and detachable means electrically 35 connecting the terminals, one to each of the bus rings, said detachable means also serving as connections through which the racks are supported by the bus rings.

2. In combination with the supporting 40 frame of a lamp which frame includes a base member having a substantially centrally arranged, vertical post; a rheostat embodying a pair of bus rings spaced apart longitudinally along and insulated from the post; and a plurality of angularly spaced resistance 45 elements arranged about the post, each element embodying a wire-rack having non-conductive characteristics, terminal caps applied to opposite ends of the rack, said caps having conductive characteristics, and resistance wire wound about said rack between and terminally connected to said caps; and detachable means electrically connecting the caps, 50 one to each of the bus rings, said detachable means also serving as connections through which the racks are supported by the bus rings.

55 In witness that I claim the foregoing I have hereunto subscribed my name this 23rd 60 day of March 1926.

HARRY D. BROWN.
